UNITED STATES PATENT OFFICE.

GEORGE SCHNECK, OF OIL CITY, PENNSYLVANIA.

CROZE.

1,358,585.

Specification of Letters Patent.

Patented Nov. 9, 1920.

Application filed April 18, 1919. Serial No. 290,976.

To all whom it may concern:

Be it known that I, GEORGE SCHNECK, a citizen of the United States, residing at Oil City, in the county of Venango and State 5 of Pennsylvania, have invented certain new and useful Improvements in Crozes; and I do hereby declare the following to be a full, clear, and exact description of the invention, such as will enable others skilled in the art 10 to which it appertains to make and use the same.

This invention relates to a cooper's croze, such as employed for cutting the grooves in the staves of a barrel, short distances inwardly from the ends of the barrel, after the staves have been assembled in barrel formation, and the primary object of the invention is to provide a croze as specified which includes a main supporting body or board 20 shaped to fit over the top of a portion of a barrel which body board adjustably carries a tool head, and to provide means for adjusting the position of said tool head with the respect to the body board, for regulating the distance from the upper edge of the barrel staves, that the groove is cut.

A further object of this invention is to provide a tool head which carries a plurality of blades, and to provide means 30 whereby the position of said blades with the respect to the head may be regulated to regulate the cutting depth of the cutting tool.

With the foregoing and other objects in view, this invention consists in such novel 35 features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views and in which:

Figure 1 is a top plan of the croze,

Fig. 2 is a side elevation of the croze,

Fig. 3 is a vertical section on the line 3—3 of Fig. 2,

Fig. 4 is a detail cross section through the tool head,

Fig. 5 is a horizontal section through the tool head, and

Fig. 6 is a section on the line 6—6 of Fig. 5.

Referring more particularly to the drawing, 1 indicates the main body board of the croze which is preferably constructed of

wood and has its outer or long edge convexly cut as indicated at 2 and its inner relatively short edge concavely cut as indicated at 3. The edges 2 and 3 are concentric.

The body 1 of the croze is provided with an elongated opening 4 extending therethrough, near its concaved edge 3, through which opening the tool head carrying rod 5 and the adjusting rod 6 extend. The tool 65 head carrying rod 5 is provided with a longitudinally extending key way 7 in which keys 8 and 9 are seated. The key 8 is carried by a metal plate 10 which is attached to the upper surface of the body 1 by means of bolts 12 70 while the key 9 is carried by a lug 13 which is formed upon and depends from the plate 10, extending completely through the body 1.

The rod 5 is provided with a transversely extending recess 14 formed therein near its upper end, in which recess a portion of the periphery of a washer 15 is seated. The washer 15 is carried by the adjusting screw 6 for rotation therewith, and this adjusting screw engages threaded opening 16 which 80 extends through the lug 13 as clearly shown in Fig. 3 of the drawing. A relatively large head 17¹ is formed upon the upper end of the adjusting screw 6 and it overhangs the upper end of the rod 5. The head 17¹ has 85 its periphery knurled for facilitating the gripping thereof by the thumb and finger of the operator for rotating the feed screw to adjust the rod 5 vertically through the opening 4.

The rod 5 has a shoulder 17 formed thereon near its lower end and the rod is reduced outwardly from the shoulder 17, and screw threaded to form the shank 18 which extends through the tool carrying head 19. 90

The tool carrying head 19 comprises a plate 20 the edges of which are curved as indicated at 21 in Fig. 5 of the drawing for fitting against the interior of a barrel. The plate 20 is provided with a recess 22 100 formed in its under surface, and with ribs 23 which extend along each side of the recess. A tool clamping plate 24 is inserted in the recess 22 and clamped against the cutting tools 25, 26, and 27 by a nut 28¹ which is 105 mounted upon the threaded shank 18.

The tools 26 and 27 are placed next to each other, upon the side of the shank 18 oppositely from the tool 25 and they have their cutting ends pointed, as shown at 28, and 110 oppositely beveled as clearly shown in Fig. 6 of the drawing, the cutting edge of one

tool adapted to score the upper line of the groove in the barrel space while the cutting edge of the other tool scores the lower line of the groove. The tool 25 has a drag head 29 formed upon its cutting end, the cutting end 30 of which is square, for cutting out the wood between the two scored lines made by the points 28 of the tools 26 and 27, for making the groove about the interior of the barrel in the staves thereof, upon the movement of the croze about the barrel.

In reducing the invention to practice, certain minor features of construction, combination and arrangement of parts may necessitate alterations to which the patentee is entitled provided such alterations are comprehended within the scope of what is claimed.

What is claimed is:

20. In a croze, the combination, of a body board provided with an opening extending therethrough near one edge of the same, a

plate attached to the upper surface of said body board, a lug formed upon said plate and extending through said opening, a tool 25 carrying rod extending through said lug, said rod provided with a longitudinal key way, keys formed upon said lug and located one at each side of the board and seated in said key way for preventing rotation of said 30 tool carrying rod, an adjusting screw adjustably carried by said lug and passing through the opening in the board, means connecting said adjusting screw and said rod for moving the rod upon movement of 35 the adjusting screw, and a tool carrying head carried by the lower end of said rod.

In testimony whereof I affix my signature in presence of two witnesses.

GEORGE SCHNECK.
